SPARK QUENCHING ARRANGEMENT

Willie Saville, Huyton, Liverpool, England, assignor to Associated Telephone & Telegraph Company, Chicago, Ill., a corporation of Delaware

Application March 26, 1938, Serial No. 198,182
In Great Britain April 6, 1937

4 Claims. (Cl. 175—294)

The present invention relates to spark quenching arrangements for use in telephone or like systems and is particularly concerned with the prevention of destructive arcing at points where 5 highly inductive circuits are suddenly or repeatedly opened, for instance in connection with the control or operation of step-by-step automatic switches which are electromagnetically driven.

10 Hitherto reduction of arcing in such circumstances has generally been effected by the use of condensers and resistances of suitable value connected in series across the contacts opening the circuit or alternatively connected across the 15 source of energy producing the arc.

Good results have been achieved by this method for many years but it has the disadvantage that the assemblage of condensers and resistances is somewhat costly where a large number of quenching circuits are required and also a good deal of mounting space is taken up. The object of the 20 invention is to provide spark quenching facilities by means involving a considerable reduction in cost and also an appreciable saving in mounting space.

According to the invention use is made of a solid body composed of material the resistance of which is substantially the same for both directions of current flow but which decreases with 25 increase of voltage. Material of this type may be considered as substantially an insulator as long as the applied voltage does not exceed a critical value but when it is subjected to a higher voltage it breaks down momentarily and passes 30 quite a considerable current. This material is thus very well suited to the absorption of high inductive voltages which would otherwise produce sparking.

One material having these properties comprises 35 a mixture of silicon carbide with carbon and/or tungsten or molybdenum which is agglomerated under pressure and subsequently baked, the resulting mass having a resistance-current characteristic which is substantially 40 hyperbolic. This material is commercially known as "Thyrite".

The invention will be more fully understood from the following description of two methods of carrying it into effect which should be taken in 45 conjunction with the accompanying drawings comprising Figs. 1-7.

Fig. 1 shows a spring pile-up using a "Thyrite" washer to separate the interrupter springs.

Fig. 2 shows a top view of Fig. 1.

Fig. 3 shows a disc of "Thyrite" to which a

plurality of circuits are connected for common spark-quenching arrangement.

Fig. 4 diagrammatically illustrates the circuits having the common spark-quenching arrangement of Fig. 3.

Fig. 5 shows a "Thyrite" disc having ridges.

Fig. 6 is a cross section taken on the line 6—6 of Fig. 5.

Fig. 7 shows another "Thyrite" disc having 10 metal-sprayed spots on one of its surfaces for circuit connections.

One known method in the use of "Thyrite" is shown in the Siegmund Patent 2,052,318, issued August 25, 1936 wherein "Thyrite" is made into 15 a washer of suitable shape and thickness and is mounted in a spring pile-up between a pair of cooperating contact springs. An arrangement of interrupter springs separated by a "Thyrite" washer is shown in Figs. 1 and 2 which represent 20 a side elevation and a plan respectively and indicate the arrangement used in a known type of automatic switch. Of the various components which are held together by the bolts 1 the top spring 2 is the driving spring for the switch 25 wipers and is stressed by the movement of the magnet armature by means of a lever engaging it near its left-hand extremity. Springs 3 and 4 are the actual interrupter springs and spring 3 is 30 of substantially the same shape as spring 2 and is arranged to be engaged near its left-hand end by a further member operated by the armature so as to open the interrupter contacts 5 when the magnet is fully operated. The lower spring 4 is provided with a soldering tag 6 and a side extension 7 carrying the appropriate contact 35 point. The lowermost member 8 of the pile is conveniently made of a double wedge shape as shown so as to permit adjustment by suitable 40 operation of bolts 1.

The various members of the assembly are kept 45 apart and electrically insulated by insulating washers 9 but the member 10 which in the ordinary construction would also be an insulator is in this case made of resistance material of substantially rectangular shape corresponding to the upper insulator 9. In this case good electrical contact is preferably secured by metal spraying both surfaces of the "Thyrite" washer 10.

It will be understood that a similar arrangement could be adopted for use between the impulsive contacts of an ordinary dial switch. This would permit some alteration to be made in the 50 normal substation circuit since this is usually ar- 55

ranged so as to give a spark quenching effect at the dial switch contacts.

According to the invention it is more convenient to mount the spark absorbing material remote from the interrupter springs and it is proposed that the same unit shall be arranged to quench sparks from a plurality of separate circuits. For example the preferred arrangement shown in Figs. 3 and 4 might be adopted in which the washer made of "Thyrite" is pressed into the form of a circular disc about the size of a shilling and one surface, the lower surface in Fig. 3, is completely metal-sprayed to form a common connecting point. The upper surface is sprayed as shown at a plurality of disconnected points 11, eight in number, which are equally spaced round the circumference of the disc. This enables eight circuits to be quenched from the same disc, connections being made by way of the individual leads 12 extending to the separate points and the common lead 13 extending to the lower surface. These circuits are shown in detail in Fig. 4 wherein 22, 32 and 42 indicate relays or magnets each having an inductive winding with one terminal connected to the negative pole of battery B and the opposite terminals each connected by a conductor 12 to a separate metal sprayed spot 11 on the "Thyrite" disc. Each conductor 12 is connected to a spring contact which cooperates with an associated spring contact such as shown at 21, 31 and 41. The bottom of the "Thyrite" disc is metal sprayed at 11 and is connected by way of conductor 13 to ground. The battery B is a common battery and has its positive pole grounded. In Figs. 5 and 7 the metal sprayed spots 11 are connected to inductive circuits (not shown) identical to the circuits shown in Fig. 4.

Assuming now that contacts 21 are closed and that the winding of relay or magnet 22 is energized over its obvious circuit and that shortly thereafter contacts 21 open. Since relay 22 is inductive, an abnormal increase in voltage or inductive discharge takes place when contacts 21 open. In ordinary circuits this inductive discharge would be dissipated in the form of a spark at contacts 21 but in this case an inductive discharge path has been provided by way of conductor 12, metal sprayed spot 11, the "Thyrite" disc, the metal sprayed bottom 11, and by way of conductor 13 to ground. Since this inductive discharge current has a considerably higher voltage than the normal voltage of battery B and also since this inductive discharge current exceeds the critical value, the "Thyrite" disc, insulating qualities break down and the inductive discharge current passes thru the "Thyrite" disc and over conductor 13 to ground instead of sparking thru the open contacts 21 to ground. The other inductive circuits connected to conductor 12 all operate in the same manner as just described.

From the foregoing description it will be obvious that a single disc of "Thyrite," when metal sprayed and connected to a plurality of separate inductive circuits as shown, forms a common

spark quenching circuits for a plurality of inductive circuits.

Should it be found necessary to increase the surface resistance between the various spot connections 11 to prevent leakage between such spots, the die for pressing the "Thyrite" disc could be arranged to undulate the surface, such as for instance, by the formation of a series of concentric ridges around each spot as shown in Figs. 5 and 6.

As another alternative to increase still further the usefulness of the disc, one or both sides could be metal-sprayed at a plurality of disconnected spots lying around a common connecting spot in the centre as shown in Fig. 7. With this arrangement it will be appreciated that the quenching circuits provided by the disc will be across the surface between the respective spots rather than through the thickness of the material as previously and consequently the minimum thickness is determined by mechanical rather than electrical considerations. With the dimensions assumed as many as eight or more circuits could readily be quenched through the same piece of material, in which case the saving in space becomes an important consideration.

I claim:

1. In a spark quenching arrangement comprising a plurality of inductive circuits, a single body of material the resistance of which is substantially the same for both directions of current flow but which decreases with increase of voltage, and individual and separate connecting means connecting each said circuit to said single body, and means whereby said single body in combination with said individual connecting means comprises a common spark quenching circuit for said plurality of circuits to dissipate the inductive discharge current caused by the opening of any one or more of said circuits thereby preventing sparking in said circuits at their open circuit points.

2. A spark quenching arrangement as claimed in claim 1 in which said single body comprises a disc and each said connecting means is individually and separately connected to one side of said disc while the opposite side of said disc is connected to ground so that the inductive discharge current flows through the material of said disc.

3. A spark quenching arrangement as claimed in claim 1 in which said single body is in the form of a disc and a common ground connection is made to one side of said disc while each said individual circuit connecting means is individually connected to an individual point on the other side of said disc.

4. A spark quenching arrangement as claimed in claim 1 in which a common ground connection in combination with said individual connecting means are all individually connected to one surface of said body so that current due to the inductive voltage flows substantially along the surface of the material of said body.

WILLIE SAVILLE.
